**SNAG PREVENTIVE SINKER OR SIMILAR ARTICLE
FOR TREBLE FISH HOOKS**

Robert E. Spencer, Rte. 2, Nokesville, Va. 22123

Filed Apr. 2, 1968, Ser. No. 11,266

Term of patent 14 years

Int. Cl. D22—08

U.S. Cl. D22—30

FIG. 1

FIG. 2

FIG. 3

FIG. 1 is a front elevation of a snag preventive sinker or similar article for treble fish hooks;

FIG. 2 is a top plan view of FIG. 1; and

FIG. 3 is a sectional view on line 3—3 of FIG. 2.

I claim:

The ornamental design for a snag preventive sinker or similar article for treble fish hooks, substantially as shown.
